(57) **CLAIM**

The ornamental design for an electrical connector housing, as shown and described.

DESCRIPTION

FIG. 1 is a front, top, and right side perspective view of a first embodiment of an electrical connector housing showing my new design;

FIG. 2 is a rear, bottom, and left side perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof, the left side view being a mirror image of FIG. 7;

FIG. 8 is a cross-sectional view taken along line 8-8 in FIG. 3;

FIG. 9 is a cross-sectional view taken along line 9-9 in FIG. 3;

FIG. 10 is a cross-sectional view taken along line 10-10 in FIG. 3;

FIG. 11 is a cross-sectional view taken along line 11-11 in FIG. 3;

FIG. 12 is a front, top, and right side perspective view of a second embodiment of an electrical connector housing showing my new design;

FIG. 13 is a rear, bottom, and left side perspective view thereof;

FIG. 14 is a front view thereof;

FIG. 15 is a rear view thereof;

FIG. 16 is a top plan view thereof;

FIG. 17 is a bottom plan view thereof;

FIG. 18 is a right side view thereof;

FIG. 19 is a left side view thereof;

(Continued)

FIG. 20 is a cross-sectional view taken along line 20-20 in FIG. 14;
 FIG. 21 is a cross-sectional view taken along line 21-21 in FIG. 14;
 FIG. 22 is a cross-sectional view taken along line 22-22 in FIG. 14;
 FIG. 23 is a cross-sectional view taken along line 23-23 in FIG. 14;
 FIG. 24 is a front, top, and right side perspective view of a third embodiment of an electrical connector housing showing my new design;
 FIG. 25 is a rear, bottom, and left side perspective view thereof;
 FIG. 26 is a front view thereof;
 FIG. 27 is a rear view thereof;
 FIG. 28 is a top plan view thereof;
 FIG. 29 is a bottom plan view thereof;
 FIG. 30 is a right side view thereof, the left side view being a mirror image of FIG. 30;
 FIG. 31 is a cross-sectional view taken along line 31-31 in FIG. 26;
 FIG. 32 is a cross-sectional view taken along line 32-32 in FIG. 26;
 FIG. 33 is a cross-sectional view taken along line 33-33 in FIG. 26; and,
 FIG. 34 is a cross-sectional view taken along line 34-34 in FIG. 26.
 The broken lines illustrate portions of the electrical connector housing that form no part of the claimed design.
